UNITED STATES PATENT OFFICE

MARTIN L. WILLIAMS, OF CHICAGO, ILLINOIS, ASSIGNOR, BY DIRECT AND MESNE ASSIGNMENTS, TO WILLIAMS-FREESE CORPORATION, OF CHICAGO, ILLINOIS, A CORPORATION OF ILLINOIS

SUPPORT FOR PORTABLE TYPEWRITERS

Application filed May 7, 1928. Serial No. 275,883.

The present invention relates more particularly to a support for portable typewriters comprising in combination a typewriter supporting tray mounted for limited sliding movement on a drawer which latter is adapted for sliding engagement with a suitable desk, table, cabinet, console or the like.

The invention is particularly adaptable for use with so-called portable typewriters which are relatively small, compact, replicas of standard size typewriting machines. In using typewriters, particularly of the portable type, it is necessary to place them on a suitable support during use, which generally takes the form of a convenient flat top, for instance, of a table, cabinet or other similar support, it being necessary to clear away a space large enough to accommodate the typewriter and permit working papers or sheets to be laid alongside the typewriter. There is no means of locking or otherwise holding the typewriter in a fixed relative position, and in use it will gradually work itself away from the original position in which it was placed. This is objectionable for many reasons which are more or less obvious.

Having in mind that in recent years the sale and use of portable typewriters has grown to the point where a large number of them are being used, and also having in mind certain objections resulting from their use at the present time, I have perfected a novel form of support therefor comprising in combination a universally interchangeable supporting tray adapted to receive portable typewriters of all sizes, makes, and shapes, which tray is adapted for sliding movement in a drawer resembling the drawer of an ordinary desk, which drawer is itself adapted for sliding movement in a conventional type desk, cabinet, console, table or the like in place of the conventional drawer now occupying that space.

The front wall of the drawer of the present invention has a hinge connection, the arrangement being such as to permit it to be dropped to a horizontal position when the drawer is in use, said front wall in that position functioning to afford an auxiliary sup-

port for the typewriter and its supporting tray.

The invention will find wide use in hotels, clubs, Pullman cars, homes, and as a matter of fact in any place where it is desired to use a portable typewriter.

Among the objects of the present invention are to provide a support for portable typewriters comprising in combination a universally interchangeable typewriter supporting tray mounted for sliding movement in a drawer, which latter is itself adapted for sliding movement in a suitable table, cabinet, console, desk or the like; to provide a construction of the character described in which, when not in use, the sliding drawer can be slid into a cabinet, desk, console, or the like, and from the outside resemble in appearance an ordinary drawer; to provide in a construction of the character described a hinged front wall capable of being dropped to an open position, in which position said front wall lies flat and horizontal; to provide a construction of the character described in which the base of the drawer as well as the front wall thereof may be provided with tracks, guides, or other suitable devices on which and by which the supporting tray carrying the typewriter may be guided in and out; to provide in a construction of the character described means for limiting the outward movement of the typewriter and its supporting tray to prevent accidental disengagement of the typewriter and its supporting tray from the drawer; to provide a flat supporting tray on which the typewriter rests and to which it is secured to move therewith as a unit; to provide means for temporarily locking the typewriter in a relatively fixed position at any desired point intermediate the length of the track; to provide a construction in which the unit comprising the typewriter and its supporting tray may be removably mounted in the drawer in such a manner that the typewriter may be left permanently in the drawer and concealed when not in use and may be removed and replaced at will; to provide a construction in which the typewriter supporting tray is universally applicable to portable typewriters of all makes, sizes and designs; to provide a construction in

which the portable typewriter may be readily removable from and replaceable on said tray with a minimum loss of time and expenditure of labor; to provide a construction in which the typewriter and its supporting tray may be bodily removed as a unit from any drawer, or the typewriter itself may be removed from engagement with a supporting tray; to provide a construction in which the typewriter supporting tray is slidable relative to the drawer, and in turn the drawer is slidable into and out of a cabinet, table, desk, or the like; to provide a construction which can be quickly adapted for use in conventional desks, cabinets, tables, or the like, and which is exceedingly efficient in operation, economical to manufacture and install and of high utility in operation, and in general to provide improvements of the character hereinbefore and hereinafter referred to.

Other objects, features and advantages of the present invention will be more apparent from the following detailed description.

In the drawings, Fig. 1 is an elevational view, partly in perspective, illustrating a desk or table equipped according to the present invention.

Fig. 2 is a vertical sectional view taken on a line cut through the desk or table illustrated in Fig. 1 while it was in closed position.

Fig. 3 is a transverse sectional view taken on line 3—3 of Fig. 2.

Fig. 4 is a fragmentary cross sectional view illustrating in detail the snap latch for locking the hinged front wall of the drawer in closed position.

Fig. 5 is a fragmentary view, partly in section, illustrating the means for limiting excess outward movement of the typewriter and its supporting tray, and also illustrating a snap latch for locking the typewriter supporting tray in extended position.

Fig. 6 is an enlarged fragmentary cross sectional view of the latch member illustrated in Fig. 4.

Fig. 7 is a vertical sectional view taken on line 7—7 of Fig. 5.

Referring more in detail to the drawings, 1 designates as a whole a conventional type of table, desk, console or cabinet provided with the supporting legs 2. The element 1 may be provided with a hinged top cover 3 adapted to be retained in a raised position by means of the conventional support 4. While I have illustrated the element 1 as being equipped with the hinged top cover 3, it is obvious that it is not at all necessary for the success of the present invention that a hinged top cover such as 3 be employed. The element 1 may present merely a flat or other shaped top, such as illustrated at 5. A panel 6 may be mounted on the top cover 3 and slightly spaced therefrom to provide a space adapted to receive stationery, paper and the like.

Oppositely spaced shelf members 7 may be

provided on the support 1 on which may be mounted for slidable movement relative to the support a drawer 8. This drawer 8 may have a tongue and groove engagement, or any other kind of engagement with the side shelf member 7, the element 8 being adapted to slide in and out of the support in the same manner as a conventional drawer. The drawer 8 may be provided with side walls 9 slightly spaced below the stationary top member 5 of element 1 and with a number of small drawers 10 and pigeon holes 11.

The drawer 8 may be provided with a front panel 12 mounted for hinged movement relative to the drawer 8 through the medium of combination hinge braces 13, which latter function to hold the front panel in a substantially horizontal position when said panel is dropped to an open position from its normal vertical position, closing the front of the drawer 8. Suitable lugs 14 may be provided to prevent the drawer 8 from sliding too far out of the element 1. A conventional snap latch 15 adapted to be maintained in an extended position by means of the spring 16 may be carried by the panel 12, said latch being adapted when the panel is in closed position to engage a suitable indentation in the lower surface of the stationary top member 5. One or more hand knobs 17 may be provided on the panel 12.

As a feature of the present invention, spaced opposite parallel channelled track or guide members 18 may be mounted upon the base of the drawer 8. The guides or tracks 18 are adapted for sliding interlocking relationship through the medium of angular members 19 with a typewriter carrying tray 20 upon which may be mounted a portable typewriter 21 the arrangement being such that the typewriter and its supporting tray are slidable as a unit on the tracks or guides 18.

An upstanding lug 22 adapted to be engaged by a projecting lug 23 carried by one or both of the angular members 19 may project from one or both of the tracks or guides 18 to limit the outward movement of the typewriter and its supporting tray, thus preventing excess outward movement.

A conventional snap latch 24 mounted on a pin 25 slidably carried by the bracket 23' may be maintained in an extended position by a spring 26 whereby said snap latch may engage any one of a number of spaced indentations disposed along the length of one or both of the tracks or guides 18 to lock the typewriter and its supporting tray in relatively fixed position when the typewriter is slid outwardly for use. In the utilization of the device, assume that the structure illustrated in Fig. 1 is in closed position, that is, the drawer 8 has been slid into the element 1 and the front panel closed. In this description it will be assumed that the typewriter is concealed within the element 1. By grasp-

ing the handle 17 the front panel may be opened and dropped to a horizontal position, the pivoted braces 13 maintaining said panel in horizontal position. The drawer 8 is then 5 slidably pulled outwardly, for instance, until the lugs 14 engage each other.

It might be well to here point out that while I have illustrated these lugs 14 they are not at all essential in carrying out the 10 invention, as in normal operation the drawer 8 would not normally be pulled out too far. The typewriter supporting tray provided with a handle 27 may be then slid outwardly until the snap latch 24 engages in one of the 15 indentations on one or both of the guides or tracks 18. It is not possible to pull the support out too far on account of the fact that the lugs 23 and 22 will contact, thus preventing further outward movement. The typewriter is now in position to be used.

It will be noted that the drawers 10 and 20 pigeon holes 11 are preferably carried by the drawer 8, hence they will be within easy 25 reach of the typewriter user. It is also to be noted that the inner face of the panel 12 is provided with metal strips 28 which are in effect elongations of the track or guide 18, and as a feature of the present invention it is also to be noted that this front panel 12 in open 30 position functions as a support for the front end of the typewriter.

When it is desired to slide the typewriter back into the element 1, the foregoing operation is reversed.

As pointed out heretofore in the objects 35 of the invention, the typewriter supporting tray is universally interchangeable for any type, size or design of typewriter. The invention may be carried out by mounting the typewriter on the typewriter supporting tray and thereafter concealing the typewriter in the element 1 when not in use, or the invention is equally applicable to use in situations 40 where users have their own typewriters which they carry from place to place. The typewriter supporting tray 20 being universally interchangeable can be used with equal facility with different makes and sizes of typewriters. When it is desired to entirely remove the typewriter supporting tray 20, the bracket holding the lug 23 may be removed, thus permitting the tray to be slid out of engagement with the track or guide 18.

While I have shown a particular form of 55 track or guide 18 and angular track engaging portions 19, it is to be understood that I do not in any way wish to be limited to the particular construction illustrated, as any type of track or guide and connection there- 60 between with the typewriter supporting tray may be utilized within the scope of the invention.

The lugs 22 and 23 may be disposed on one or both of the tracks and sides of the tray. 65 It is also obvious that the snap latch 24 may

be disposed on either or both sides of the tray.

One of the main advantages of the present invention is that the assembly comprising the 70 slideable drawer 8 and slideable tray 20 may be readily mounted in conventional desks, cabinets, tables, or the like, to replace conventional types of drawers, or the entire assembly, including the element 1, may be manufactured and sold as a unit. I have illustrated 75 the panel 12 as being vertically disposed in closed position to close the front of the drawer and keep out dust, thus making the part holding the typewriter dust-proof. It is obvious, of course, that this movable panel may 80 be swung underneath the base of the drawer 8 in closed position, in which event the front of the drawer would be open, or it may be dispensed with altogether, in which event the front of the drawer 8 would be open, and the 85 front edge of the typewriter support tray 20 could not with safety be pulled out any further than the front edge of the base of the drawer 8.

I claim as my invention:

In combination, an element provided with a guide track on the upper surface thereof, and a supporting tray mounted for limited 90 slideable movement in said guide track and relative to said element, said element comprising a drawer having a movable front panel adapted, when the tray is slid outwardly on said guide track, to be dropped to a horizontal position to act as a partial support for said tray, and means for locking 100 the tray in a desired position upon the said element, said means comprising a spring operated pin carried by the tray, the guide track being provided with a plurality of indentations with which the pin is adapted to 105 operate.

In testimony whereof I affix my signature.

MARTIN L. WILLIAMS.
